UNITED STATES PATENT OFFICE.

FORREST E. BINGHAM, OF NEW BEDFORD, MASSACHUSETTS.

LIQUID FILTERING AND DELIVERING APPARATUS.

1,230,099.

Specification of Letters Patent. Patented June 19, 1917.

Application filed November 8, 1916. Serial No. 130,165.

To all whom it may concern:

Be it known that I, FORREST E. BINGHAM, a citizen of the United States, residing at New Bedford, in the county of Bristol and 5 State of Massachusetts, have invented new and useful Improvements in Liquid Filtering and Delivering Apparatus, of which the following is a specification.

This invention has for its object to 10 provide apparatus adapted particularly to filter oil which has become charged with impurities and foreign matter during its use as a lubricant, and to deliver the filtered liquid at any suitable point, permitting it to be 15 again used.

The invention is embodied as a whole in a liquid filtering and delivering apparatus comprising, in combination, a centrifugal filter basket, a fixed curb inclosing the 20 basket and having a central filtered liquid outlet in its bottom, a fixed centrifugal pump casing having a liquid inlet communicating with the curb outlet, and a marginal delivering outlet, a rotor inclosed by said casing 25 and adapted to force liquid from the inlet to the outlet thereof, and a driving spindle engaged with said basket and rotor to simultaneously rotate the same.

The invention is also embodied in certain 30 improvements incidental to the general purposes of the invention, all which are herein-after described and claimed.

Of the accompanying drawings forming a part of this specification,—

35 Figure 1 represents a vertical sectional view of an apparatus embodying the invention;

Fig. 2 represents a horizontal section on line 2—2 of Fig. 1;

40 Fig. 3 represents a top plan view of the rotor;

Fig. 4 represents a side or edge view of the rotor;

45 Fig. 5 represents a sectional view of the rotor, a portion of the hub being broken away;

Fig. 6 represents a sectional view of the rotor, showing the hub unbroken;

50 Fig. 7 represents a vertical section of the upper spindle bearing hereinafter referred to;

Fig. 8 represents a section on line 8—8 of Fig. 7;

55 Fig. 9 represents a fragmentary sectional view of the pump casing without the rotor.

The same reference characters indicate the same or similar parts in all the views.

In the drawings, 12 represents a vertical spindle driven by a suitable motor, a portion of the casing of which is shown at 13 in 60 Fig. 1. Any suitable type of motor may be employed adapted to rotate the spindle at a relatively high rate of speed, say from twelve to fifteen hundred revolutions per minute.

65 A lower bearing for said spindle is shown at 14, said bearing preferably forming a part of the fixed centrifugal pump casing hereinafter described. An upper spindle bearing is shown at 15, and is preferably 70 provided with a flange 16 supported as hereinafter described by the said pump casing, the bearing 15 being provided with a series of vertical passages 17 (Fig. 7) adapted to permit oil to flow by gravity 75 from the bottom of a filter curb 18 to the said pump casing.

The centrifugal pump casing is of generally circular form, and is preferably composed of a lower section 19 and an upper 80 section 20, said sections being provided with marginal flanges connected by bolts 21. The opposed sides of the sections are recessed to collectively form a rotor chamber 22 (Fig. 9), a circular oil conducting passage 23 surrounding said chamber, and a passage 24 connecting the chamber 22 and passage 23. The upper section 20 is provided with an annular seat 25 to which the bearing flange 16 is bolted.

90 The bottom of the curb 18 bears on and is attached to the flange 16, which constitutes a seat for said bottom. The curb bottom is open at its center and communicates with the passages 17, which collectively constitute an outlet for filtered oil from the curb 18, and an inlet admitting the filtered oil to the central portion of the rotor chamber. To the upper end of the spindle 12 is attached a collar 26 having a downwardly projecting tubular extension 27 surrounding the bearing 15 and provided with an outwardly projecting flange 28. The flange extension 27 supports a filter basket and imparts rotation from the spindle to 100 said basket.

105 The filter basket, as here shown, is composed of a perforated annular inner member 29, a perforated annular outer member 30, and a perforated annular intermediate 110

member 31, said members being provided respectively with flanges 29^a, 30^a and 31^a. The flanges 29^a and 31^a are riveted together at 32, and the flange 30^a is riveted at 32^a to the driving flange 28. The said flanges collectively form the bottom of the annular basket. The space between the basket members 29 and 31 may contain loose filtering material such as sawdust. The 10 space between the members 30 and 31 may contain filtering material such as cloth applied by winding a layer of cloth on the outer surface of the member 31, thus forming a laminated filter 33. The members 29 15 and 31, the flanges of which are riveted together at 32, are separable as one part from the member 30, so that the cloth may conveniently be wound on and removed from the member 31 when it is removed from the member 30. The attachment of the outer member 30 to the driving flange 28 by rivets 32^a causes a positive rotation of the 20 said outer member, the frictional connection between the outer member 30 and the intermediate member 31 caused by the laminated filter 33 being sufficient to cause the intermediate and inner members of the basket to rotate with the outer member.

Oil to be filtered is admitted to the filter 30 basket through a hopper or funnel 34 located on the cover 25 of the curb, and receiving oil through a conduit 36.

In the rotor chamber 22 is located a rotor, the form and construction of which are best shown by Figs. 3, 4, 5 and 6. Said rotor 35 preferably includes an annular hollow portion 37 having a hub 38 rigidly secured to the spindle, said hub having a tapering oil conducting portion 38^a. The rotor also includes an annular top portion 39 which is of dished or frusto-conical form, and is provided with tangential curved buckets 40, extending across the space between the bottom and top portions 37 and 39, the rotor being 40 preferably cast in a single piece. Said buckets subdivide the space between the portions 37 and 39 into tangential passages 45 through which oil is forced centrifugally outward into the conducting passage 23 surrounding the rotor chamber. The central opening of the rotor section 39 is enlarged, so that oil conducted from the curb by the vertical passages 17 is discharged within the buckets 40.

It will now be seen that, when the spindle 55 12 is rotated, the filter basket and the rotor rotate in unison with the spindle, so that oil delivered at the center of the filter basket is thrown centrifugally outward into the curb through the filtering materials or bodies above described, the filtered oil flowing 60 through the vertical passages 17 into the central portion of the rotor chamber and being then thrown outward centrifugally by the rotor into the oil conducting

passage 23. Said passage, as shown by Fig. 2, is preferably eccentric to the rotor and is provided with a marginal oil delivering outlet 41, preferably arranged tangentially, said outlet forming a part of a delivering 70 conduit, which may extend to any desired elevated point. The filtered oil may therefore be conducted to an elevated tank and stored therein for further use.

Having described my invention, I claim: 75

1. A liquid filtering and delivering apparatus comprising, in combination, a centrifugal filter basket, a fixed curb inclosing the basket and having a central filtered liquid outlet in its bottom, a fixed centrifugal pump casing have a liquid inlet 80 communicating with the curb outlet, and a marginal delivering outlet, a rotor inclosed by said casing and adapted to force liquid from the inlet to the outlet thereof, and a 85 driving spindle engaged with said basket and rotor to simultaneously rotate the same.

2. A liquid filtering and delivering apparatus comprising a fixed casing having a rotor chamber and a liquid conducting passage surrounding said chamber, and provided with a marginal outlet, a fixed curb located above said casing and having an outlet 90 communicating with the central portion of said chamber and permitting filtered liquid to flow by gravity from the curb to the rotor chamber, a vertical spindle extending through said chamber into the curb, a centrifugal filter basket located in said curb, and a rotor located in said chamber, 100 said basket and rotor being connected with the spindle to rotate therewith, and the rotor and casing constituting a centrifugal pump whereby liquid thrown centrifugally outward by the basket in the curb, and flowing therefrom to the rotor chamber, is forced centrifugally outward to said passage and through the filter to said marginal outlet. 105

3. A liquid filtering and delivering apparatus comprising a fixed casing having a 110 rotor chamber and a liquid conducting passage surrounding said chamber and provided with a marginal outlet, a fixed curb located above said casing and having an outlet communicating with the central portion of said chamber and permitting filtered liquid to flow by gravity from the curb to the rotor chamber, a vertical spindle extending through said chamber into the curb, a sleeve attached to the upper end of the spindle and having a tubular flanged extension projecting downwardly to a point near the bottom of the curb, an annular centrifugal filter basket supported by the said extension and rotated thereby, and a rotor located in 115 said chamber and attached to the spindle to rotate therewith, said rotor having buckets formed to throw filtered liquid centrifugally outward from the chamber. 120

4. A liquid filtering and delivering appa- 130

5 ratus comprising a fixed casing having a rotor chamber, a liquid conducting passage surrounding the chamber and provided with a marginal delivering outlet, said casing being composed of a lower section having a lower bearing and an upper section having an enlarged central opening, an upper bearing formed to conduct liquid into said opening, and a seat surrounding said opening, a 10 curb having an apertured bottom attached to said seat, the opening constituting an outlet through which filtered liquid may flow by gravity from the curb to the rotor chamber, a vertical spindle journaled in said bearings, and extending through said chamber and opening into the curb, a centrifugal filter basket located in said curb and a rotor located in said chamber, said basket and rotor being connected with the spindle to 15 20 rotate therewith.

5. A liquid filtering and delivering apparatus comprising a fixed casing having a rotor chamber and a liquid conducting passage surrounding said chamber and provided with a marginal outlet, a fixed curb located above said casing and having an outlet communicating with the central portion of said chamber and permitting filtered liquid to flow by gravity from the curb to 25 30 the rotor chamber, a vertical spindle extending through said chamber into the curb, a centrifugal filter basket located in said curb

and a rotor located in said chamber and composed of a flat annular bottom portion having a tapering hub attached to the spindle, a dished annular top portion and tangential buckets subdividing the space between the bottom and top portions into tangential passages adapted to deliver liquid at the periphery of the rotor. 35 40

6. In combination, a fixed curb having an outlet in its bottom, a fixed vertical bearing projecting into said curb, a vertical spindle journaled in said bearing, a basket-driving flange attached to said spindle and located 45 within said curb, an annular filter basket composed of perforated inner, outer and intermediate members having flanges forming the bottom of the basket, the flange of the outer member being positively secured to 50 said driving flange, while the flanges of the inner and intermediate members are separable with said members from the flange of the outer member, and a laminated filter carried by the intermediate member, and constituting a frictional connection between the said intermediate and outer members, the inner and intermediate members forming an annular chamber adapted to contain loose filtering material. 55 60

In testimony whereof I have affixed my signature.

FORREST E. BINGHAM.
